(57) **CLAIM**

The ornamental design for a luminaire, as shown and described.

DESCRIPTION

FIG. 1 is a perspective view of a luminaire, showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a bottom plan view thereof;

FIG. 7 is a top plan view thereof;

FIG. 8 is a perspective view of another embodiment of the new design for a luminaire;

FIG. 9 is a front elevation view of the luminaire of FIG. 8;

FIG. 10 is a rear elevation view of the luminaire of FIG. 8; FIG. 11 is a right-side elevation view of the luminaire of FIG. 8; FIG. 12 is a left-side elevation view of the luminaire of FIG. 8; FIG. 13 is a bottom plan view of the luminaire of FIG. 8; FIG. 14 is a top plan view of the luminaire of FIG. 8; FIG. 15 is a perspective view of another embodiment of the new design for a luminaire; FIG. 16 is a front elevation view of the luminaire of FIG. 15; FIG. 17 is a rear elevation view of the luminaire of FIG. 15; FIG. 18 is a right-side elevation view of the luminaire of FIG. 15; FIG. 19 is a left-side elevation view of the luminaire of FIG. 15; FIG. 20 is a bottom plan view of the luminaire of FIG. 15; FIG. 21 is a top plan view of the luminaire of FIG. 15; FIG. 22 is a perspective view of another embodiment of the new design for a luminaire; FIG. 23 is a front elevation view of the luminaire of FIG. 22; FIG. 24 is a rear elevation view of the luminaire of FIG. 22; FIG. 25 is a right-side elevation view of the luminaire of FIG. 22; FIG. 26 is a left-side elevation view of the luminaire of FIG. 22; FIG. 27 is a bottom plan view of the luminaire of FIG. 22; FIG. 28 is a top plan view of the luminaire of FIG. 22; FIG. 29 is a perspective view of another embodiment of the new design for a luminaire; FIG. 30 is a front elevation view of the luminaire of FIG. 29; FIG. 31 is a rear elevation view of the luminaire of FIG. 29; FIG. 32 is a right-side elevation view of the luminaire of FIG. 29; FIG. 33 is a left-side elevation view of the luminaire of FIG. 29; FIG. 34 is a bottom plan view of the luminaire of FIG. 29; FIG. 35 is a top plan view of the luminaire of FIG. 29; FIG. 36 is a perspective view of another embodiment of the new design for a luminaire; FIG. 37 is a front elevation view of the luminaire of FIG. 36; FIG. 38 is a rear elevation view of the luminaire of FIG. 36; FIG. 39 is a right-side elevation view of the luminaire of FIG. 36; FIG. 40 is a left-side elevation view of the luminaire of FIG. 36; FIG. 41 is a bottom plan view of the luminaire of FIG. 36; and, FIG. 42 is a top plan view of the luminaire of FIG. 36. The broken lines shown represent unclaimed subject matter and form no part of the claimed design.
